UNITED STATES PATENT OFFICE.

GEORGE H. KITCHEN, OF NEW YORK, N. Y.

IMPROVED PORTABLE APPARATUS FOR MANUFACTURING ILLUMINATING-GAS.

Specification forming part of Letters Patent No. 36,096, dated August 5, 1862.

To all whom it may concern:

Be it known that I, GEORGE H. KITCHEN, of the city and State of New York, have invented, made, and applied to use a certain new and useful Improvement in Portable Gas Apparatus; and I do hereby declare the following to be a full, clear, and exact description of my said invention, reference being had to the annexed drawings, making part of this specification, wherein—

Figure 1 is a vertical section lengthwise of the retort, and Fig. 2 is a cross-section.

Similar marks of reference denote the same parts.

Portable gas apparatus has heretofore been made with a retort in a furnace, and the gas itself, formed from oil, allowed to pass into said retort and go off in the gaseous form to a gasometer.

The nature of my said invention consists in the employment of a peculiar character of tile beneath the retort to equalize the action of the fire on the same and prevent the retort burning, and at the same time render said retort much more efficient in consequence of the uniformity of the heat; and in order to prevent heat from the furnace passing out into the cellar, where such portable gas apparatus is usually placed, I employ a double casing to the furnace, which tends to retain the heat, and, in connection with the aforesaid tile, to equalize the heat in its action upon the retort.

In the drawings, *a* is a furnace formed by a double casing of sheet metal, as shown, leaving a space for a stratum of air, ashes, plaster, or other non-conducting material, to retain the heat in the furnace as much as possible. This furnace is also lined with soapstone or fire-brick at *b*.

c is the grate, and *d* is the ash-draw.

e is a retort of any convenient construction or size, and below said retort is my improved tile *f*, of fire-brick, soapstone, or similar material. It is well known that fires burn the most intensely in the center. I therefore make my

said tile *f* thickest in the middle and thinner toward the ends, so that the temperature of the retort throughout shall be as nearly uniform as possible, and the non-conducting space around the furnace conspires to aid in equalizing the heat by preventing the outside of the furnace becoming chilled. The furnace is to be covered with movable plates *g* and *h*; and *i* is the base of the smoke-pipe.

The retort is heated by the coals introduced through the openings covered by *g* *h*, and said fuel is not to come up higher than the top edges of the tile *f*, as in Fig. 2.

The oil from which the gas in this portable apparatus is made is to be supplied by a suitable cock to the siphon-pipe *k*, and the gas conveyed away, as at *l*, to a suitable reservoir.

The heavy coal-oils, which are now the cheapest for making gas from, contain an excess of carbon and are apt to smoke. I therefore fill my retort with strips of wood, packed in closely; and I find that the gas passing among said strips of wood in the presence of the heat is so purified and changed in its nature, by combining with the gases driven off from said wood, that smoking is prevented. These strips of wood will last for several days, and when removed they are found to be a hard quality of charcoal.

What I claim, and desire to secure by Letters Patent, is—

1. The tile *f*, formed thicker in the middle than at the ends and applied in the manner specified to equalize the heat upon the retort, as set forth.

2. In combination with the said tile *f*, a double casing, *a*, to aid in retaining heat and equalizing the action thereof on the retort, as specified.

In witness whereof I have hereunto set my signature this 2d day of June, 1862.

GEO. H. KITCHEN.
